Primary Examiner — Austin Murphy

(57) **CLAIM**

The ornamental design for a flip and stretch VR headset as shown and described.

DESCRIPTION

FIG. 1 is a front perspective view of a flip and stretch VR headset showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is an enlarged detail view taken from portion 9 of FIG. 6.

The broken lines in the drawings depict portions of the flip and stretch VR headset that form no part of the claimed design; The broken lines in the drawings indicate enlarged portions which form no part of the claimed design.
